DISPLAY APPARATUS

Joseph C. Conn, Boonton, N. J.

Application June 25, 1935, Serial No. 28,262

5 Claims. (Cl. 40—142)

This invention relates to an improvement in display apparatus of the type shown in my co-pending application Serial No. 11,789 filed March 19, 1935.

5 It is an object of the invention to provide improved means for retaining the background members on the back or base of the display apparatus.

One embodiment of the invention is shown in 10 the accompanying drawing, in which:

Figure 1 is a front elevation of a display apparatus embodying the invention.

Fig. 2 is an enlarged transverse section taken on the line 2—2 of Fig. 1.

15 Fig. 3 is a perspective view on a smaller scale of a portion of the means for retaining the background members on the back or baseboard of the apparatus.

The illustrative display apparatus comprises 20 a frame which may include a channel-shaped member having a back or base portion 1 and longitudinally-extending flanges 2 and transverse end pieces 3. Inner surfaces of the channel may be rendered light-absorbent or non-reflecting by a suitable coating of paint or the like.

As shown in Fig. 1, the information or data 25 to be displayed is represented or indicated on or by markers 4, a common form of which is made of celluloid or other suitable material such as sheet metal. The markers may comprise top portions of any desired conformation and tabs or arms extending rearwardly therefrom engaged and held by the background members presently 30 to be described.

The frame above-mentioned carries between 35 its flanges 2 background members 5 which provide means for releasably retaining the markers in display condition and are of such character 40 as to make the markers stand out distinctly and be readily visible by contrast with said background in all usual conditions of illumination. For such purpose, I employ a resilient material, preferably screen material having portions in 45 convolute form and presenting a reticulated surface effect such as netting, screen or the like of a mesh size and color depending on the intended use.

As shown in Fig. 2, each individual background 50 member 5 is bent into substantially an inverted U shape. Each individual member 5 extends between end members 3 and parallel with side members 2. The several members 5 are in substantial contact with each other and they are 55 adapted to receive between them the tabs extend-

ing from the markers 4, and by pressure thereagainst retain the markers in position on the display apparatus.

The apparatus as thus far described is similar to the apparatus disclosed in said co-pending application Serial No. 11,789, reference to which is hereby made for a more detailed description.

For retaining the background members 5 on the base 1, a plurality (three in the illustrative embodiment) of plates 6 having upstanding arrow-like heads 7 and 7A are secured in spaced relationship transversely the base 1. The plates 6 may be made of suitable metal and welded or otherwise secured to the base 1. The arrow-like heads 7 and 7A may be formed by a stamping operation and then bent upwardly to the position shown in Fig. 3.

Referring to Figs. 2 and 3 it will be noted that the heads 7 located at one side of the plate 6 are 20 higher than the plates 7A located on the other edge of the plate 6 and that the heads 7 and 7A are in staggered relationship, i. e., the heads 7 are located opposite openings between heads 7A and the heads 7A are located opposite openings 25 between heads 7, so that when a background member 5 is placed over a head 7 the barb-like projections 8 of the head 7 will engage both legs of the inverted U-shaped member 5 at one level of the wire mesh, while barb-like projections 9 of 30 two adjacent heads 7A will engage the legs of the member 5 at a lower level of the wire mesh. This arrangement prevents undue distortion of the strands of the wire mesh and securely retains the several background members in position on the 35 baseboard 1.

Because of the shape and relationship of the heads 7 and 7A, as shown particularly in Fig. 2, the wire mesh 5 may be readily forced down over the heads but cannot be raised due to the action 40 of the barb-like projections 8 and 9 under which projections the longitudinal strands of the wire mesh lodge.

While the heads 7 and 7A in the illustrative embodiment are shown as carried by or formed 45 as a part of plates 6 secured to the base 1, it will be understood that the heads 7 may be formed on or secured to the base 1 without departing from the invention.

While the background members 5 are shown 50 as separate members the several background members or any series of them may be made from a continuous sheet of screening bent to form convolutions, all as shown and described in my co-pending application Serial No. 11,789. 55

While heads 7 and 7A are preferably formed as shown in Figs. 2 and 3 with barb-like projections 8 and 9 to engage and hold the wire mesh of which the background members 5 are made, it will be understood that the invention is not to be limited to such a construction as other forms of screen-retaining members having one or more barb-like projections may be used without departing from the invention as defined in the subjoined claims.

10 I claim:

1. Display apparatus comprising a base member, marker-retaining means of resilient screen material, and means for securing the marker-retaining means to the baseboard comprising retaining-members extending from the base and having barb-like projections adapted to engage

the screen material and hold it in position on the base.

2. Apparatus according to claim 1 in which the retaining-members are carried by a plate secured to the base. 5

3. Apparatus according to claim 1 in which the retaining-members have arrow-shaped heads with barb-like projections at either side thereof.

4. Apparatus according to claim 1 in which the retaining-members vary in height to engage the wire screen at different levels. 10

5. Apparatus according to claim 1 in which the retaining-members are located in parallel rows but in staggered relationship. 15

JOSEPH C. CONN.
